JOINT CONSTRUCTION

Edgar M. Tucker, South Pasadena, Calif.

Application January 6, 1937, Serial No. 119,216

9 Claims. (Cl. 108—26)

This invention relates to joint construction.

The general object of the invention is to provide an improved joint construction for sealing the joint between layers of material such as composition roofing.

A further object of my invention is to provide a novel flashing construction.

A more specific object of my invention is to provide a flashing strip having a novel means for holding a strip in place.

Another object of my invention is to provide a flashing strip having apertures therein through which plastic material extends to hold the strip in place.

15 An additional object of my invention is to provide a flashing strip having apertures through which plastic projecting members extend and wherein a wire mesh member is engaged by these projections to hold the parts assembled.

20 A further object of my invention is to provide a flashing strip including a metal member having apertures through which plastic holding projections extend and wherein these projections are locked by mesh members which extend above and

25 below the flashing strip and are secured to the projections and to the adjacent portions of the building structure and the up turned roofing.

Other objects and the advantages of my invention will be apparent from the following description taken in connection with the accompanying drawings, wherein:

Fig. 1 is a fragmentary perspective view showing a roof flashing embodying the features of my invention;

35 Fig. 2 is a fragmentary perspective view showing the manner of laying and securing superimposed plies in position;

Fig. 3 is a view similar to Fig. 2 showing one step in the securing;

40 Figs. 4, 5 and 6 are fragmentary sectional details through the material showing the homogeneous plastic or binder passing through the apertures;

Fig. 7 is a section through the joint shown in

45 Fig. 1;

Fig. 8 is a fragmentary elevation partly in section showing a modification of my invention;

Fig. 9 is a perspective view showing the flashing member used in connection with the modification;

50 Fig. 10 is a sectional view showing the modification;

Fig. 11 is a fragmentary perspective view showing my invention employed in connection with the laying of shingles;

Fig. 12 is a plan view of the metal strip; Figs. 13 and 14 are fragmentary, plane views showing modifications of the metal strips; and

Fig. 15 is a section taken on line 15—15 Fig. 14.

Referring to the drawings by reference characters I have shown my invention as embodied in a roof flashing which is indicated generally at 10.

As shown the flashing is arranged in conjunction with a roof deck 11 and a parapet wall 12. 10 The roof deck is shown as having covering of plastic material 13 thereon which may be any suitable preparation and may include asphalt, coal tar, or other material.

15 In the application the plastic material is preferably first mopped upon the roof deck 11 as shown in the drawings to a width substantially equal to that of the roof covering and then a layer of covering material such as paper 14 is placed upon the mopped material. This material 14 which may be roof paper of suitable composition is provided with apertures 15 along one of its edges. These apertures 15 may be of suitable size, configuration and arrangement and as shown in the drawings are circular and are spaced uniformly apart. When the layer of paper 14 is laid upon the plastic material 13 which adheres to the roof deck 11, the paper adheres to the plastic material and a portion of the plastic material passes through the apertures 15 and projects above the paper 14 as shown at A in Figs. 1 and 4 forming projections.

20 The roof deck is then mopped with plastic material for a distance corresponding to the width of the next layer of roofing to be laid and the edge of the previously laid layer is mopped as at 16. The projections A are simultaneously flattened. Also the lower face of the next layer is also mopped as at 17 (see Figs. 2 and 5). As shown in Fig. 3 the second layer is then swung upward and over so that the parts are brought into the position shown at 18 in Figs. 1 and 6 so that the second layer of paper is firmly held in place. The plastic material thus forms a continuous homogeneous mass from the roof deck 11 through the apertures 15 and into contact with the lower face of the second layer of paper so that not only is a tight joint provided but the entire area is secured into one unitary body.

25 The operation is continued until the parapet wall is reached at which point the edge 19 (as shown in Fig. 1) of the layer of paper adjoining the parapet wall is bent up after the parapet wall has been mopped with plastic as at 20. This plastic passes through the apertures 15 in this 30

portion and on the outer surface a mopping of plastic 21 is placed. The plastic 21 extends under a base flashing angle member 22 which is thus secured to the mopped material 20 and 21. The 5 base flashing 22 includes apertures 23 through which the plastic 20 passes as indicated at B in Figs. 1 and 7. The outer surface of the upstanding part of the base flashing 22 is then covered with a flashing 24. This flashing 24 engages the 10 mopped portion 20 of the parapet wall 12 and also engages the plastic material B which passes through the apertures 23 of the base flashing 22 so that the wall is held in one unit.

The flashing 24 includes a plurality of rows of 15 spaced apertures 25 through which the plastic material 20 passes as indicated at C and over a portion of the upper section of the flashing 24 a mopping 25' of plastic material is placed. Over the plastic 25' on the flashing 24 at the upper 20 part thereof and extending above the flashing I arrange a wire fabric 26 which is of mesh of such size that the plastic material 20 will pass therethrough as also will the plastic material 25'. As a result the fabric 26 is firmly embedded in the 25 plastic thus holding all of the plastic projections 25 in place. After this is done a plastic covering 27 is arranged over the upper portion of the flashing 24 covering the projections and the mesh member 26 as shown in Fig. 1. As a result of 30 this construction the roofing and flashing are held as one unit by the homogeneous interlocking projections A, B, and C formed by the plastic material which passes through the apertures. Nails 30 may be employed to hold the parts assembled 35 until the plastic sets.

In Fig. 11 I show a modification of my invention wherein shingles 40 are provided with apertures 41 at one end. The roof deck receives a coating 42 of plastic material which passes 40 through the apertures 41 and as each course of shingles is laid and is secured as by nails 43, the plastic material passes from the roof deck through the apertures 41 and engages the lower face of the portion of each shingle thereabove.

In Figs. 8, 9 and 10 I have shown a modified 45 type of flashing which is indicated generally at 50. As shown the flashing 50 is arranged in conjunction with a roof 51 and a parapet wall 52. The roof has a covering 53 which may be a composition roofing which has an up turned portion 54 engaging the parapet wall 52. This portion 54 is covered by a base flashing 54A which extends 50 upwardly as at 54B.

My flashing as shown includes a metal strip 55. 55 This strip 55 includes an upper portion 56, a lower portion 57 and an intermediate portion 58. This intermediate portion comprises a plurality of layers of the strip preferably bent flat upon themselves as shown. The upper portion 56 is provided with apertures 59 while the lower portion 57 is provided with apertures 60.

In use a coating of plastic is placed upon the 65 parapet wall 52 and the strip 55 is also covered with plastic on the rear side thereof and the strip 65 is then disposed immediately above the upper end of the portion 54B and is pushed in place thus forcing the plastic through the apertures 59 and 60 and forming projections or beads 61 and 62 which serve to hold the strip 55 in place. Nails 70 63 may be then driven through the strip 55 to serve to hold the parts united until the plastic sets.

As shown, I may arrange a mesh member 64 having folded over portions 64 arranged beneath 75 the folded over portions 58 previously described

and thus locked. The mesh member includes an upwardly extending portion 65' which extends above the portion 56 and a downwardly extending portion 66 which extends below the portion 57 onto the up turned portion 54B of the roofing. 5 The plastic projections 61 which pass through the apertures 59 also pass through the mesh portion 65 thus serving as an anchor and hold the parts in place. The projections 60 also pass through the mesh portion 66 serving to anchor the parts. 10

Beneath the folded over portions 58 I arrange a cover member 67 which may be of composition or a sheet of metal and which is securely held in place by the folded over strip and which extends downwardly over the mesh portion 66 and 15 as shown engages a plastic which is placed over the mesh portion 66 as indicated at 68. Additional plastic is also placed in engagement with the upper portion 65' of the mesh member on the outer side thereof as at 69 and this plastic 69 20 extends through the mesh portion 65 into engagement with the parapet wall 52.

From the foregoing it will be apparent that the strip 55 is locked in place by the projections 25 59 and 60 and that these projections are also held 25 in place by the mesh member 63 and it will be noted that the mesh member in turn is held in place by the plastic 68 which engages the mesh member and the upwardly extending portion 54B of the base flashing and also by the plastic 69 30 which engages the fabric and the parapet wall 52.

In Fig. 13 I show a modified form of metal strip. This strip indicated generally at 55a includes an upper portion 56a, a lower portion 57a and an intermediate portion 58a. This intermediate portion is formed similar to the intermediate portion 58 previously described and the strip shown in Fig. 13 differs from the strip previously described only in that apertures 59 triangular in shape are arranged with their bases reversed.

In Figs. 14 and 15 I show another strip indicated generally at 56b which is similar to the strip 55 previously described except that the upper and lower portions are provided with cut struck tongues 59b which leave apertures 59c in 45 the material. These tongues are shown as arranged staggered in two rows so that the tongues assume the position shown in Fig. 15. The use of the strip shown in Figs. 13, 14 and 15 is similar to that shown in connection with Fig. 12.

From the foregoing description it will be apparent that I have invented a novel joint construction which is useful in the laying of roofs, in flashing, and which in fact may be employed generally wherever it is desired to unite overlapping layers of material and to secure the overlapping layers together as a unit and to secure them as a unit to the structure on which they are applied. With my invention it will be apparent that economy of manufacture and an assurance 60 of a tight joint is secured.

Having thus described my invention I claim:

1. A building structure including a roof and a parapet wall, roofing material on said roof and including a portion turned up to engage said 65 parapet wall, said portion having apertures therein, said wall having plastic thereon passing through said apertures, a flashing strip including a lower portion overlapping the upturned portion of the roofing material and an upper portion 70 having apertures therein and engaging the plastic material on the parapet wall, the plastic material passing through the flashing strip apertures, a coating of plastic on the outer face of the apertured portion of the flashing strip, said 75

coating being homogeneous with the plastic on the parapet wall, a mesh member engaging the coating and through which the coating extends, said mesh member having its upper portion embedded in the plastic on the parapet wall and an outer coating over the first mentioned coating and the mesh member.

2. A flashing strip including a piece of material bent to include an upper portion, a lower portion and an intermediate portion which is doubled upon itself and folded to engage the lower portion, said upper and lower portions having apertures therethrough, a wire mesh member folded upon itself and secured beneath said folded over portion, said wire mesh member being bent upwardly, said mesh member also extending downwardly, said mesh member projecting above the upper portion of said strip and a cover anchored between said folded over portion and said lower portion and extending downwardly therefrom.

3. A building structure comprising a strip of metal and a coated wall, said strip having apertures therein and the coating on the wall passing through the apertures to provide locking projections, a wire mesh member secured to said strip and engaging the outer face of the strip, said locking projections extending through the mesh, and a flexible cover secured to said strip and being adapted to be arranged over the up turned portion of a roofing material.

4. In a building structure, a roof, a parapet wall extending above said roof, roofing material on the roof and including a portion up turned to engage the parapet wall, a flashing strip including a piece of material bent to include an upper portion, a lower portion and an intermediate portion which is doubled upon itself and folded to engage the lower portion, said upper and lower portions having apertures therethrough and plastic material engaging said parapet wall and including portions projecting through said apertures to form locking projections.

5. A building structure comprising a strip of metal and a coated wall, said strip having apertures therein and the coating on the wall passing through the apertures to provide locking projections, a wire mesh member engaging the outer face of the strip and adapted to engage the wall thereabove and the up turned portion of a roof, said locking projections extending through the mesh, and a flexible cover secured to said strip and engaging the outer face of the mesh member, said cover extending downwardly and being adapted to be arranged over the up turned portion of a roofing material and a plastic coating over the strip and the said mesh member.

6. A flashing comprising a strip of metal, said strip being adapted to engage a coated wall, said strip including an upper and lower portion, said upper and lower portions having apertures therein adapted to receive a wall coating to provide locking projections, a wire mesh member secured to said strip, one portion of said wire mesh member being bent upwardly to engage the outer face of the upper portion of the strip and adapted to engage the wall thereabove and the other mesh portion being bent downwardly, and a flexible cover secured beneath said folded over portions and engaging the outer face of the downwardly bent mesh member, said cover extending downwardly and being adapted to be arranged over the up turned portion of a roofing material.

7. In a building structure a coated wall, a strip adapted to engage the coated wall, said strip in-

cluding an upper and lower portion, said upper and lower portions having apertures therein and with the coating on the wall adapted to pass through the apertures to provide locking projections, a wire mesh member secured to said strip, one portion of said wire mesh member being bent upwardly to engage the outer face of the upper portion of the strip and adapted to engage the wall thereabove and the other mesh portion being bent downwardly, said locking projections being adapted to extend through the mesh, and a flexible cover secured beneath said folded over portions and engaging the outer face of the downwardly bent mesh member, said cover extending downwardly and being adapted to be arranged over the up turned portion of a roofing material and a plastic coating over the upper portion of the strip, the upper portion of said mesh and the downwardly extending cover member.

8. In a building structure, a roof, a parapet wall extending above said roof, roofing material on the roof and including a portion up turned to engage the parapet wall, a flashing strip including a piece of material bent to include an upper portion, a lower portion and an intermediate portion which is doubled upon itself and folded to engage the lower portion, said upper and lower portions having apertures therethrough, a plastic material engaging said parapet wall and including portions projecting through said apertures to form locking projections, a wire mesh member folded upon itself and secured beneath said folded over portion, said wire mesh member being bent upwardly and having the locking projections extending through the mesh to form an anchor for the projections, said mesh member also extending downwardly and having the locking projections passing therethrough to form an anchor member, and a cover anchored between said folded over portions and extending downwardly over said up turned portion of said roofing.

9. In a building structure, a roof, a parapet wall extending above said roof, roofing material on the roof and up turned to engage the parapet wall, a flashing strip including a piece of material bent to include an upper portion, a lower portion and an intermediate portion which is doubled upon itself and folded to engage the lower portion, said upper and lower portions having apertures therethrough, a plastic material engaging said parapet wall and including portions projecting through said apertures to form locking projections, a wire mesh member folded upon itself and secured beneath said folded over portion, said wire mesh member being bent upwardly and having the locking projections extending through the mesh to form an anchor for the projections, said mesh member also extending downwardly and having the locking projections passing therethrough to form an anchor member, said mesh member projecting above the upper portion of said strip, a plastic material passing through said mesh above the strip and engaging the parapet wall, said mesh member extending onto said up turned portion of roofing, a coating of plastic material extending through said mesh member and engaging said up turned portion of roofing and a cover anchored between said folded over portions and extending downwardly over said up turned portion of said roofing.
